(57) **CLAIM**

The ornamental design for a display screen or portion thereof having an animated graphical user interface, as shown and described.

DESCRIPTION

FIG. 1 is a front view a display screen or portion thereof having an animated graphical user interface showing a first image;

FIG. 2 is a front view of the display screen or portion thereof having the animated graphical user interface showing a second image;

FIG. 3 is a front view of the display screen or portion thereof having the animated graphical user interface showing a third image;

FIG. 4 is a front view of the display screen or portion thereof having the animated graphical user interface showing a fourth image;

FIG. 5 is a front view of the display screen or portion thereof having the animated graphical user interface showing a fifth image;

FIG. 6 is a front view of the display screen or portion thereof having the animated graphical user interface showing a sixth image;

FIG. 7 is a front view of the display screen or portion thereof having the animated graphical user interface showing a seventh image;

FIG. 8 is a front view of the display screen or portion thereof having the animated graphical user interface showing an eighth image;

FIG. 9 is a front view of the display screen or portion thereof having the animated graphical user interface showing a ninth image; and,

FIG. 10 is a front view of the display screen or portion thereof having the animated graphical user interface showing a tenth image.

The appearance of the animated graphical user interface sequentially transitions from FIG. 1 to FIG. 10. The process in which a figure transitions to another figure forms no part of the claimed design.

The dot-dashed broken lines depict a boundary of the display screen or portion thereof and form no part of the claimed design.
